UNITED STATES PATENT OFFICE.

HENRY S. STOVALL, OF WEATHERBY, MISSOURI.

DESIGN FOR A BADGE.

SPECIFICATION forming part of Design No. 34,467, dated May 7, 1901.

Application filed April 9, 1901. Serial No. 55,111. Term of patent 14 years.

To all whom it may concern:

Be it known that I, HENRY S. STOVALL, a citizen of the United States, residing at Weatherby, in the county of Dekalb and State of Missouri, have invented and produced a new and original Design for a Badge; and I do hereby declare the following to be a full, clear, and exact description of the same, reference being had to the accompanying drawing, forming a part thereof.

Said drawing represents an elevation of a badge embodying my design, the leading feature of which is a monogrammic assemblage of the conventional compass, square, and hatchet.

Referring to the drawing, 1 designates the head of the hatchet, and 2 is the handle of said hatchet, which extends horizontally from the head 1.

3 is a representation of a compass, with its pivot 4 upward and the lower ends of its arms merging into the head of the hatchet and the remote end of its handle.

5 is the representation of a square, with its angle resting upon the handle of the hatchet 25 and its arms passing in rear of the legs of the compass.

6 is a large letter "G" occupying the space within the compass within the square and between the two. The face of the legs of the 30 compass, as well as its pivot 4, is ornamented, as indicated, thus presenting a pleasing effect when the whole is worn as a badge.

Having thus described my invention, what I claim is—

The design for a badge as herein shown and described. 35

In testimony whereof I affix my signature in presence of two witnesses.

HENRY S. STOVALL.
